CLAIM

The ornamental design for a hydroponic planter, as shown and described.

DESCRIPTION

FIG. 1 is a top perspective view of a hydroponic planter, showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a front perspective view showing the environmental use thereof.

The broken line portion of the figures is included to show unclaimed subject matter only and forms no part of the claimed design.

1 Claim, 8 Drawing Sheets(56)
